The ornamental design for a scraper plane, as shown and described.

DESCRIPTION

FIG. 1 is a perspective view of a scraper plane, showing our new design.

FIG. 2 is a right side elevation view of the scraper plane of FIG. 1.

FIG. 3 is a left side elevation view of the scraper plane of FIG. 1.

FIG. 4 is a back elevation view of the scraper plane of FIG. 1.

FIG. 5 is a front elevation view of the scraper plane of FIG. 1.

FIG. 6 is a top plan view of the scraper plane of FIG. 1; and,

FIG. 7 is a bottom plan view of the scraper plane of FIG. 1.
